Chicago, Ill., a corporation of Delaware

Application March 10, 1939, Serial No. 260,888

12 Claims. (Cl. 271—88)

The present invention relates to a ventilating and accelerating device adapted for use with printing presses, and particularly at the sheet delivery and stacking part of the press with or 5 without means provided for spraying non-offset material upon the delivered sheets for preventing offset or set-off in printing.

In printing presses of the type indicated, the imprinted sheets are successively delivered by a 10 suitable delivery means to a locus where each sheet is released and allowed to drop by gravity onto the top of a stack of previously dropped sheets. This is usually termed "air dropping" and it requires an appreciable interval of time 15 before it is completely dropped to repose on top of the stack. The time it takes to so drop the sheets imposes a limitation upon the speed of the press which must be regulated to deliver the sheets only as fast as the sheet may "air drop" 20 to the stack.

Also, in such presses it is usual to provide means, at the delivery thereof, for spraying non-offset material upon the delivered sheet or the dropping sheet to prevent offset of ink from one 25 sheet to another. There is usually surplus or strayed particles of the sprayed material which floats around and contacts the parts of the machine requiring, after a time, a shut-down of the press and a cleaning up of the accumulated 30 material.

Among the objects of the present invention is to provide a novel means for and method of so ventilating and accelerating the delivery and stacking part of the press as to effectively carry 35 away such surplus or strayed material and to prevent its accumulating in and on the machinery, and also to so produce the ventilating draft of air as to create a partial vacuum between the released and dropping sheet and the 40 top of the stack as to cause a rapid descent of the sheet upon the stack. By thus shortening the time of "dropping" the frequency of sheet delivery and dropping is greatly increased and, hence, the speed of operation of the press is like- 45 wise increased.

In printing the speed of operation of the press is a very important factor. Any feature which has the effect of limiting such speed and which can be so changed as to give the advantage of 50 speeding up the press is a considerable improvement. The present invention accomplishes such improvement and advantage.

An illustrative form of novel means for these purposes comprises an enclosure or housing around the stacking means and about the de-

livery locus for the delivered sheets. Such means preferably comprises curtains at the sides of the press and at the front end of the press, and with an upright wall behind the stack and extending up close to the under side of the delivery means. 5 The curtains may be so weighted to contact the floor and be held in substantially taut condition. These make for an enclosure or housing which is open at the top but has a surrounding or enclosing wall. In or at the floor there is an exhaust outlet connected to suitable exhaust means adapted to produce a down draft of air into and through the housing and about the sheets; the dropping sheet and the sheets of the 10 stack.

Other objects, advantages, capabilities, features, process steps, and the like, are comprehended by the invention as will later appear and as are inherently possessed by the invention.

Referring to the drawings:

Fig. 1 is a longitudinal part elevational and part sectional conventional view of a press, ventilating means, and exhaust means;

Fig. 2 is a similar transverse view of the same;

Fig. 3 is a view similar to Fig. 2 but on an enlarged scale and showing an alternate form of exhaust means; and

Fig. 4 is a view similar to Fig. 3, with a still further form of exhaust means.

Referring more in detail to the drawings, the 30 embodiments selected to illustrate the invention are shown in connection with a printing press 1 having a printing couple 2 through which runs a web 3 from a paper roll 4 by way of suitable rollers 4^a to a delivery means 5 which is 35 generally and conventionally shown. The delivery means may be of any known construction and which is usually used in printing presses of this type. It may have grippers to grip the imprinted and cut sheet so as to move the sheet 40 to the delivery or "air-drop" locus 6 where the grippers release the sheet to permit it to drop, such a last delivered sheet being designated at 7.

Beneath the locus 6 is a stack table 8 which may be suspended from chains 9 and 10, or the 45 like, which are preferably so connected to the side frame parts 11 and 12 of the press 1 as to be adjusted or let out to accommodate for the increasing height of the stack of sheets 13 on the table 8. Adjacent the delivery end of the conveyor is a cross frame part 14 connected to the 50 ends of the side frame parts 11 and 12.

Above the delivery and sheet drop locus 6 is located a suitable spraying device 15 designed to downwardly spray non-offset material toward 55

and upon the top of the imprinted sheet 7 as it is delivered or air dropped so as to distribute over the surface of that sheet discrete particles of material which act to prevent offset of ink from one sheet to another of the stack. The material is projected in the form of fine sprays 16 and misty clouds 17 which spread over the sheet 7, as conventionally shown on the drawings. Some of the sprayed material may stray and float over the edges of the sheet 7 and contact with and adhere to the parts of the press machinery and accumulate thereon so that later it is necessary to shut down the press and clean up the accumulated material.

15 One of the objects of the present invention is to so ventilate the space about the stack 13 and the sheet 7 as to entrain and carry away the surplus and strayed particles of material or like foreign suspended matter, and to prevent their accumulating on the machinery, the same being exhausted with or without a filtering means, to the exterior of the press room. The ventilating is, therefore, effected by producing a down draft of air from above the locus 6, and around the sheet 20 7 and the stack 13, as more fully explained hereinafter.

25

For obtaining the desired results of the present invention, there is provided an enclosure or housing around the locus 6 and the stack 13. An illustrative form of enclosure comprises pendant curtains 18, 19 and 20 at the sides and at the front of the delivery part of the press, and are hung from and connected to suitable supporting means 21, 22 and 23 on the side and front frame parts 11, 14 and 12. These supporting means may be in the form of rods and the upper part of the curtains may be slidably supported on such rods so that the curtain may be so slid as to open the curtains for affording access to the interior of the enclosure. The curtains may be made of flexible material, such as canvas or the like, and the upper edges of the curtains are preferably held in close contact with the frame parts 11, 14 and 12 to prevent leakage of air therebetween. The curtains extend to and contact with the floor 24 and may have weights 25, 26 and 27 at the lower ends of the curtains so as to hold the curtains in substantially taut condition and not be materially inwardly bulged under the partial vacuum in the enclosure.

50 The curtains may have vertical partings intermediate the widths thereof so as to provide for opening the curtains at such partings whereby ready access may be had to the interior of the enclosure. The vertical edges 28 and 29 (see Fig. 3) of the curtains at such partings may be joined or closed by any suitable joining or closing means 30, such as a lacing, or a "zipper", or buttons, etc., the showing on the drawing in Fig. 3 being general and conventional for any suitable form of joining means.

The fourth wall of the enclosure is located in spaced relation to the rear of the stack, and it comprises a vertical wall 31 extending upward from the floor to and proximate to the under side of the delivery means 5. This wall may be in the form of a curtain if desired. The side curtains are preferably closely connected, to prevent leakage, to the vertical edges of the wall 31 at the rear ends of these curtains. At the forward ends thereof these curtains are connected to or continued integrally with the front curtain. Corner posts 32 and 33 may be provided to laterally support or brace the curtains. The curtains and the wall 31 thus constitute an enclosure or hous-

ing which when the curtains are closed admit air only at the open top or mouth of the enclosure.

In the forms shown in Figs. 1 and 2 there is an exhaust outlet 34 in the floor 24, a suitable grid or the like being located in such outlet. Connected to the outlet 34 is a duct 35 leading to a collection chamber 36 in which may be located a suitable filter 37. From the chamber 36 leads a duct 38 to the intake of an exhaust blower 39 having a discharge duct 40 in the outlet of which 10 may be a louver shutter 41. The blower 39 may be supported on a suitable stand 42. 5

In the form shown in Fig. 3, the exhaust outlet 43 is at the inner end of the exhaust duct 44, the latter being of rectangular cross-sectional form 15 and leading out of the enclosure close to or at the floor and from a side of the enclosure.

In the form of Fig. 4 the exhaust outlet 45, of grid form, is provided in the top of a shallow exhaust duct 46, also rectangular in cross-sectional form. The outlet is placed centrally beneath the stacking table 8 so that the downward draft of air about the stack in the enclosure will have equal paths of travel. The duct 46 is of such low height and of such width that the truck 25 used for moving the stack table and stack out of the enclosure may pass over the duct and also span it. The truck is wheeled into the enclosure from a side thereof. To do so the parting of the side curtain is opened and the curtain parts 30 pushed to one side to provide the necessary opening through which the truck may be wheeled into and out of the enclosure. The exhaust outlets 34, 43 and 46 are, in all forms shown, at the bottom of the enclosure or substantially so. 35

In operation the delivery means successively delivers freshly imprinted sheets to the air dropping locus 6 where they are released. The spraying means 15 projects non-offset material toward each sheet 7. At the same time the exhaust blower 39 effects or produces a down draft of air through the upper opening or mouth of the enclosure and into the latter. The flow of air is represented by the various arrows shown on the drawings. As the air is drawn down past the edges of the sheet 7 it entrains the strayed and surplus particles of sprayed material and carries them in suspension downwardly in the spaces between the stack 13 and the walls of the enclosure, to the underside of the stack table 8, and thence into the exhaust outlet. Such dust laden air is then cleaned in the collecting chamber 36, and then discharged in cleaned condition to the atmosphere by way of the discharge duct 40.

An important feature of the present invention is the speeding up or hastening of the "air-drop" of the delivered sheet. This is effected by the creation, by reason of the down draft of air in the enclosure, of a partial vacuum in the space between the delivered sheet 7 and the top of the stack 13. This effects a sucking action under the sheet 7 and causes it to rapidly descend onto the stack; much more rapidly than if the sheet were left to air-drop or descend by gravity. In this way the stacking of the sheets is effected at greater speed, and hence the press may be accordingly speeded up to print and deliver the paper.

It is to be understood that the accelerating of the "drop" of the sheet 7 is effected whether or not the sheet is being sprayed as above described. 70 The invention has at least two advantages, one to accelerate the "drop" of the sheet, and another to draw away the spray dust or the like when the sheets are sprayed.

While we have herein described and upon the 75

drawings shown a few illustrative embodiments of the invention, it is to be understood that the invention is not limited thereto but comprehends other constructions, details, arrangements of parts, features, process steps, and the like, without departing from the spirit of the invention.

Having thus disclosed the invention, we claim:

1. A ventilating and accelerating device for the delivery part of a printing press having means for delivering and stacking freshly imprinted sheets, comprising an enclosure enclosing the space where the sheets are delivered and stacked, said enclosure being open at the top and having an exhaust outlet at the bottom thereof, means for creating a downward draft of air in said enclosure and about the delivered and stacked sheets to withdraw foreign suspended matter in the air and to cause a partial vacuum at all points between the top of the stack of sheets and the last delivered sheet for hastening the stacking of the latter and for affording a speedy operation of the press.

2. A ventilating and accelerating device for the delivery part of a printing press having means for delivering and stacking freshly imprinted sheets, comprising an enclosure enclosing the space where the sheets are delivered and stacked, said enclosure being open at the top and having an exhaust outlet at the bottom thereof, means for creating a downward draft of air in said enclosure and about the delivered and stacked sheets to withdraw foreign suspended matter in the air and to cause a partial vacuum between the top of the stack of sheets and the last delivered sheet for hastening the stacking of the latter and for affording a speedy operation of the press, said enclosure comprising walls of flexible and substantially non-porous material with closable partings which may be opened to afford ready access to the interior of the enclosure.

3. A ventilating and accelerating device for the delivery part of a printing press having means for delivering and stacking freshly imprinted sheets, comprising an enclosure enclosing the space where the sheets are delivered and stacked, said enclosure being open at the top and having an exhaust outlet at the bottom thereof, means for creating a downward draft of air in said enclosure and about the delivered and stacked sheets to withdraw foreign suspended matter in the air and to cause a partial vacuum between the top of the stack of sheets and the last delivered sheet for hastening the stacking of the latter and for affording a speedy operation of the press, said enclosure comprising walls of flexible and substantially non-porous material in the form of curtains pendants connected to fixed parts of the press around the delivery means thereof and extending to the floor, said curtains having joinable partings which may be opened to afford ready access to the interior of the enclosure.

4. A ventilating and accelerating device for the delivery part of a printing press having means for delivering and stacking freshly imprinted sheets, comprising an enclosure enclosing the space where the sheets are delivered and stacked, said enclosure being open at the top and having an exhaust outlet at the bottom thereof, means for creating a downward draft of air in said enclosure and about the delivered and stacked sheets to withdraw foreign suspended matter in the air and to cause a partial vacuum between the top of the stack of sheets and the last delivered sheet for hastening the stacking of the latter sheet and for affording a more speedy operation of the press.

5. A ventilating and accelerating device for the delivery part of a printing press having means for delivering and stacking freshly imprinted sheets, comprising an enclosure enclosing the space where the sheets are delivered and stacked, said enclosure being open at the top and having an exhaust outlet at the bottom thereof, means for creating a downward draft of air in said enclosure and about the delivered and stacked sheets to withdraw foreign suspended matter in the air and to cause a partial vacuum between the top of the stack of sheets and the last delivered sheet for hastening the stacking of the latter and for affording a speedy operation of the press, said enclosure comprising walls of flexible and substantially non-porous material, said curtains having weighting means at the lower portions thereof to hold said curtains in substantially taut condition, and also having joinable partings intermediate the lengths of said curtains which may be opened to afford ready access to the interior of the enclosure.

6. A ventilating and accelerating device for the delivery part of a printing press having means for delivering and stacking freshly imprinted sheets, comprising an enclosure enclosing the space where the sheets are delivered and stacked, said enclosure being open at the top and having an exhaust outlet at the bottom thereof, means for creating a downward draft of air in said enclosure and about the delivered and stacked sheets to withdraw foreign suspended matter in the air and to cause a partial vacuum between the top of the stack of sheets and the last delivered sheet for hastening the stacking of the latter and for affording a speedy operation of the press, said enclosure comprising a wall extending upwardly from the floor to proximately the underside of the delivery means of the press and rearwardly of the stacking means of the press, and curtains at the sides and at the front end of the press where the stacking means is located, said curtains being pendants connected to said sides and front end parts of the press, and also having joinable partings which may be opened to afford ready access to the interior of the housing.

6. A method of ventilating and accelerating the delivery and stacking part of a printing press where freshly imprinted sheets are delivered and stacked and which has an enclosure laterally spaced from and extending about said parts with an open top and a bottom exhaust outlet; which comprises the step of producing a down draft of air into and through the space between said enclosure and said parts for carrying away foreign suspended matter in the air and to cause a partial vacuum at all points between the top of the stack of sheets and the last delivered sheet for hastening the stacking of the latter sheet and for affording a more speedy operation of the press.

7. A method of ventilating and accelerating the delivery and stacking part of a printing press where freshly imprinted sheets are delivered and stacked and which has means for spraying non-offset material upon the delivered imprinted sheets, and has an enclosing housing laterally spaced from and extending about said parts with an open top and a bottom exhaust outlet; which comprises the steps of producing a down draft of air into and through the space between said enclosing housing and said delivered and stacked sheets, entraining strayed sprayed non-offset material to be discharged through said outlet, and creating a partial vacuum at all points between the top of the stack of sheets and the last delivered sheet for hastening the stacking of the latter sheet and for affording a more speedy operation of the press.

8. A method of accelerating the stacking of delivered sheets in a printing press having delivery and stacking means for freshly imprinted sheets, comprising the steps of producing a draft of air in the spaces at the sides of and about the stack and delivered sheet, and thereby creating a partial vacuum at all points in the space between the top of the stack and the last delivered sheet.

to accelerate the drop of said latter sheet onto the stack.

9. A method of accelerating the stacking of delivered sheets in a printing press having delivery and stacking means for freshly imprinted sheets, comprising the step of producing a partial vacuum in the spaces about said means and at all points in the space between the top of the stack and the last delivered sheet to accelerate the drop of said sheet onto the stack.

10. A ventilating and accelerating device for the delivery part of a printing press having means for delivering and stacking freshly imprinted sheets, comprising an enclosure enclosing the space where the sheets are delivered and stacked, said enclosure being open at the top and having side walls in spaced relation about the delivered sheet and the stack and extending below the stack, an exhaust outlet means below the stack in said enclosure and in spaced relation thereto, and means for creating a down draft of air in said space at all points about the delivered sheet and the stack.

11. A ventilating and accelerating device for the delivery part of a printing press having means for delivering and stacking freshly imprinted

sheets, comprising an enclosure enclosing the space where the sheets are delivered and stacked, said enclosure comprising walls disposed in spaced relation about the delivered sheet and the stack and extending below the stack to enclose a space beneath the stack, and draft creating means being so located as to draw the air in said latter space to produce a down draft of air at all points in the space about the delivered sheet and the stack.

12. A device of the character disclosed and which comprises an open top enclosure surrounding the delivery end of a printing press with at least two opposite sides of the enclosure being spaced from at least two opposite sides of the delivered sheet and the stacked sheets in said delivery end of the press to provide at least two spaces at said sides, and means below the stack of sheets and having a draft outlet in communication with the lower part of the enclosure below said stack to create a down draft of air at at least two opposite sides of the delivered sheet and the stack of sheets and in said spaces at the opposite sides thereof.

HARRY ERIKSON.

GEORGE A. HARKER.
